UNITED STATES PATENT OFFICE.

JOHN G. REED, OF LOS ANGELES, CALIFORNIA.

MUSIC-LEAF TURNER.

1,308,555.

Specification of Letters Patent.

Patented July 1, 1919.

Application filed March 18, 1918. Serial No. 223,100.

To all whom it may concern:

Be it known that I, JOHN G. REED, a citizen of the United States, residing at Los Angeles, in the county of Los Angeles and

5 State of California, have invented certain new and useful Improvements in Music-Leaf Turners, of which the following is a specification.

This invention relates to an improved 10 music leaf turner and has for its primary object to provide such a means which may be easily mounted or attached to the body of a piano, organ, or other similar body or structure, and conveniently operated by the 15 player without in any manner interfering with the player's operation of the instrument.

Another important object of the invention is to provide such a leaf turning device, for 20 turning the leaves of sheet or book music which can be operated by the player's foot without removing the foot from the instrument's pedal.

It is also another important object of the 25 invention to provide a music leaf turning device which may be applied to a piano or organ and that the actuating means may be mounted within the structure of the musical instrument without interfering with the operation of its mechanical parts and without 30 marring the artistic beauty of the instrument.

Yet another important object of the invention is to provide such a device for turning 35 the music sheets detachable from its actuating means and may be removed from the piano or organ when not in use.

And it is a further general object of my 40 invention to provide a device as above characterized, which is highly serviceable and convenient in practical use, consists of relatively few parts of simple form, and which may, therefore, be applied to pianos, organs, or to other bodies or structures where the 45 device may be used for a similar purpose at a comparatively small cost.

With the above and other objects in view, the invention consists in the novel features 50 of construction, combination and arrangement of parts to be hereinafter more fully described, claimed, and illustrated in the accompanying drawings, in which:

Figure 1 is a front elevation of a piano 55 case and showing the leaf turning device applied,

Fig. 2 is a vertical section view, partly broken away, taken at right angles to Fig. 1 in the plane of the supporting sleeve for the leaf turning pin,

Fig. 3 is a detail perspective view of the 60 sheet turning element and its associated parts,

Fig. 4 is a horizontal section on the line 4-4 of Fig. 2,

Figs. 5, 6, 7 and 8 are detail perspective 65 views of certain of the parts.

I have in the accompanying drawings shown a piano case for the application of my invention, and which I generally designate by the numeral 5. It is however, to be 70 understood, that the device may be mounted in any other structure or body in any desired manner for a similar use and that therefore, the invention is not to be limited by the present illustration.

Referring to the drawings, in detail, 6 indicates an L-shaped lever, preferably of metal. This lever has its long arm fulcrumed intermediate its ends at 6^a in the frame of the piano case 5, adjacent the pedal 7, and has near its outer end extending at right angles and in spaced relation to the piano frame, the foot plates 8 and 9. The foot plate 9 is off-set as at 9' to extend under the pedal to the relatively opposite side thereof 85 where it terminates in an upstanding lug 9^a. The plate 8 has a similar terminal lug 8^a located at the other side of the foot pedal.

The L-shaped lever 6 is further provided on the end of its short arm with an upstanding pin 10. A rod 11 is vertically mounted for turning movements in the straps 12 and has a collar 13 on its upper end to prevent its upward movement. An arm 14 projecting at right angles to the rod 11 and secured 90 thereto prevents the downward movement of the rod, 15 designates a stop plate fixed to the base of the piano case for engagement by the arm 14 to limit the turning movement of the rod 11 in one direction. The arm 14 100 has the slot 16 to receive the pin 10. The upper end of the rod 11 has the laterally projecting rod or finger 17 which is provided with an angularly bent downwardly projecting terminal 17'. A bell crank lever 18 105 is pivoted to the under side of desk board 19 as at 20, and said bell crank lever having the arms 21 and 22 disposed at right angles to each other and each provided with a longitudinal slot 23 and 24 respectively. The 110

slot 23 in the arm 21 slidingly accommodates the terminal 17' of the finger 17 on the rod 11. A short pin 25 having on its one end, the downwardly projecting finger 26 and in 5 its other end the central slot or kerf 27. This pin extends through the opening 28 in the desk board 19 and is seated for turning movement on the metal strip 29 attached to the desk board 19. This pin is free for 10 turning movement and its finger 26 slidingly engages in the slot 24 provided in the arm 22.

In mounting the rod 11 an opening is provided in the keys as shown at 30. This permits the rod to turn freely and without interfering with the operation of the keys. Also to hold the pin 25 in position, an artistically designed guide plate is mounted on 15 the top of the desk board 19 as shown at 31.

20 The detachable music rack and sheet turning member includes the sleeve or tube 32 having the arcuate slot 33 in spaced relation to its lower end. In the tube, free for turning movement, is the rod 34, said rod 25 being provided with an arm 35 extending through the slot 33. A rectangular lug 36 is provided on the lower end of the rod 34 adapted for detachable engagement in the slot 27 in the pin 25. On the arm 35 a sleeve 30 44 is frictionally engaged and is adapted to be longitudinally adjusted. Upon this sleeve the sheet receiving clip 37 is pivotally mounted as at 38. This clip may be of any suitable form, but is preferably so constructed 35 that it will not tightly clamp the music sheet but permit of the free movement of the sheet through the clip. A second clip indicated at 39 is also fixed upon the rod or arm 35, and inwardly of the latter clip. The 40 arm 35 is provided with a pivot joint as shown at 40. I also provide the arms 41 and at one of their ends with supports 42 for holding sheet or book music. These arms are pivotally attached at their other ends to 45 the sleeve or tube 32 as at 43 and adapted to fold parallel with the sleeve or tube.

It will also be seen from the above description that the clip 37 may be folded into parallel relation with the arm 35 and that 50 this clip is folded at the point 38 into parallelism with the sleeve 32 and the folded arm 35.

In assembling the music sheet rack and turning arm in operative position with the 55 actuating mechanism, the lower end of the sleeve 32 is inserted downwardly through the central opening in the plate 31 and the squared lower end of the rod 34 is engaged in the slot or kerf 27 whereby the rod 34 and 60 the part 25 are coupled for rotation as a unit. The arms 41 on the sleeve 32 and the arm 35 carried by the rod 34 are then moved outwardly and downwardly to horizontal positions and the pivoted clip 37 raised to a 65 vertical position. By shifting the sleeve 44

this clip may be adjusted to receive the lower edge of the left hand music sheet adjacent the outer vertical edge thereof, while the clip 39 receives the music sheet at a point adjacent its inner edge. The covers for the 70 sheet music are preferably seated upon the supports 42 on the outer ends of the pivoted arms 41.

In the operation of my improved sheet turning device as above described the player 75 may shift the L-shaped lever 6 to the right or left by engaging the upwardly projecting ends of the foot plates 8^a and 9^a with the toe and shifting the L-shaped lever 6 either to the right or left. The movement of said 80 lever in one direction being limited by the engagement of the lever arm 22 with a part of the piano case structure. The movement of the lever 6 in the opposite direction is limited by engagement of the arm 14 with 85 the stop plate 15. Either movement of the L-shaped lever 6 causes a relative movement of the rod 11 which actuates the bell crank lever 18 and thereby affects the rotation of the part 25 through the co-action of the 90 lever 24 on the finger 26. The rod 34 being coupled to the part 25 is thus rotated in the sleeve 32 and the arm 35 connected to the lower end of the said rod is swung from left to right or vice versa, as the case may be, 95 whereby the music sheet engaged in the clips 37 and 39 is turned.

The device operates very easily and needs only a slight pressure from the foot of the player against the projecting ends of the 100 foot plates 8 and 9 and thereby shifting the L-shaped lever on its pivot whereby the sheet or leaf turning member is operated as above described. The toe of the player's shoe may be used for this purpose without removing 105 or lifting the foot from the floor by simply pivoting the heel on the pedal and turning the toe to either side thus pressing against either of the projecting foot plates 8^a or 9^a depending upon the direction in which the 110 foot is turned.

From the foregoing description, taken in connection with the accompanying drawings, the construction, manner of operation, and several advantages of the invention will 115 be clearly and fully understood. It is to be borne in mind, however, that these features of the device are susceptible of many mechanical variations and may be embodied in numerous alternative forms. Therefore, 120 while I have shown and described what I at present believe to be the best embodiment of the invention, it is to be understood that I expressly reserve the privilege of adapting 125 all such legitimate modifications as may be freely embodied within the spirit and scope of the invention.

I claim:

The combination with a musical instrument including a tone modifying pedal; of 130

a music leaf turner including a pivoted lever supported laterally of the pedal, a plate attached to the lever provided with vertically directed terminals arranged on opposite 5 sides of the pedal and operable by the foot to oscillate the lever, a music leaf turning

arm pivotally supported upon the instrument and means connecting the terminal of the lever with the turning arm.

In testimony whereof, I affix my signature 10 hereto.

JOHN G. REED.
